US00D416548S

United States Patent [19]

Sugano et al.

[11] Patent Number: Des. 416,548

[45] Date of Patent: ** Nov. 16, 1999

[54] **CONNECTING DEVICE FOR PERIPHERAL EQUIPMENT OF AN ELECTRONIC COMPUTER**

[75] Inventors: **Yoshihiko Sugano; Yuuki Shibata, both of Tokyo; Osamu Kondo, Hoya; Noriaki Baba, Ichikawa, all of Japan**

[73] Assignee: **Kabushiki Kaisha Toshiba, Kawasaki, Japan**

[**] Term: **14 Years**

[21] Appl. No.: **29/094,932**

[22] Filed: **Oct. 14, 1998**

[30] **Foreign Application Priority Data**

Jun. 1, 1998 [JP] Japan 10-15316
